CLIP FORMING AND ASSEMBLY TOOL

Walter E. Jude, San Diego, Calif., assignor to
 Solar Aircraft Company, San Diego, Calif., a
 corporation of California

Application January 24, 1944, Serial No. 519,495

4 Claims. (Cl. 153—12)

This invention relates to tools for special forming jobs and particularly to a tool for folding a strip or ribbon of metal around a bar element, which bar element may form a portion of a yoke or other similar device.

An object of the invention is to provide a tool that is capable of rapidly bending or forming a strip of material around a bar element.

Other more specific objects and features of the invention will appear from the detailed description to follow of a particular embodiment thereof.

Briefly, the invention comprises a base member having a seat for supporting a strip, with a transverse slot extending across the seat, and a lever member fulcrumed to the base member for swinging movement with respect thereto. The lever member has on one side thereof a work-engaging surface for contacting a bar member laid across the strip immediately above the slot so that movement of the lever in one direction presses the bar and the strip down into the slot, thereby doubling the strip back around the bar on each side thereof. However, to complete the operation, the two doubled-back, juxtaposed sections of the strip need to be pressed into contact with each other, and this operation is performed in my tool by swinging the lever in the opposite direction, which causes a second surface on the lever to bear against a bolt slidable in the base member and force the bolt against the folded strip to squeeze the two sections thereof together. Thereafter the bolt is restored to normal position by a spring when the lever is released so that the finished clip can be lifted out of the tool.

In the drawing:

Fig. 1 is a perspective view of a tool in accordance with the invention in neutral position with a strip and yoke positioned therein ready for forming;

Fig. 2 is a detailed side elevation with portions in section showing the lever of the tool actuated in one direction to fold the strip about the bar of the yoke member;

Fig. 3 is a view similar to Fig. 2 showing the lever in the other extreme position to perform the final operation of pressing the two folded back sections of the strip against each other; and

Fig. 4 is a perspective view of a finished yoke and strip assembly after it has been removed from the tool.

Referring to the drawing, my tool comprises as its chief elements a base 10 and a lever 11 pivotally secured thereto for swinging movement. Thus the lever 11 is of channel shape adjacent its lower end, the two walls of the channel straddling

the upper portion of the block 10 and being pivotally secured thereto by a pin 12 which extends through both walls of the lever 11 and the block 10.

5 The block 10 is adapted to guidably support on its upper surface a work strip 13 which is to be folded about a bar portion 14 of a toggle or yoke member 15. Thus the upper surface of the block is depressed to provide a longitudinal seat only 10 slightly wider than the strip 13 so as to center the latter in desired position. Furthermore, to facilitate longitudinal positioning of the strip 13, an adjustable stop 16 is provided at the rear end of the recess, this stop 16 being secured to the base 10 by a screw 17 extending through a slot in the stop 16.

Extending downwardly from the upper surface of the block 10 and substantially perpendicular to the upper edge thereof is a slot 18 into which the 20 bar 14 and the strip 13 are pressed by engagement of tips 19 on the lever 11 with opposite ends of the bar 14. This operation is illustrated in Fig. 2 in which the lever 11 has been swung clockwise as far as it will go to press the bar 14 clear to the 25 bottom of the slot 18, leaving the two end portions of the strip extending upwardly through the slot parallel to each other.

As shown in Fig. 4, in the finished assembly 30 of the clip and yoke, the two ends of the strip are compacted tightly together throughout most of their length, thereby locking the strip to the yoke so that the assembled parts can be subject to ordinary handling without separating the strip from the yoke. This final operation of pressing

35 the two halves of the strip together is performed by swinging the lever 11 in counter-clockwise direction as far as it will go as shown in Fig. 3. This causes a face 20 on the extreme rear end of the lever to engage the rear end of a slide or bolt 40 21, which is reciprocal in a channel 22 provided therefor in the block 10 and force it to the right, causing its right end to engage the folded strip and press the two sides of the strip together immediately above the bar 14 of the yoke as shown 45 in Fig. 3.

The bolt 21 is enlarged at its right end to form a head 211 which fills the channel 22 so that when the bolt is in the retracted position shown in Fig. 2, the front face 212 is flush with one face 50 of the slot 18 except for the lower corner which is recessed as indicated at 213 to receive the bar 14 when the bolt is pressed to the right as shown in Fig. 3.

The main portion of the bolt 21 back of the 55 head 211 is cylindrical in shape and substantially

smaller than the passage 22 to provide room for a helical spring 24, which helical spring surrounds the bolt 21 and is compressed between a pair of stationary pins 25 and a collar 26, which is slideable in the passage 22 and is secured to the bolt 21 by a pin 23.

The ends of the pins 25 are press-fitted into apertures 27 in the block 10. The pins 25 not only act as stops for the forward end of the spring 24, but as stops limiting rearward movement of the head 211. Thus, in Fig. 2 the pins 25 lie against the shoulders formed by the head 211 and prevent the head from being moved any further to the left by the spring 24.

The device may be assembled by first inserting the bolt 21 into the passage 22 from the rear end and then pressing the pins 25 into place. Next the helical spring 24 is slipped into place. Then the collar 26 is slipped over the rear end of the bolt 21 and into the passage 24, and the pin 23 inserted to lock the collar to the bolt 21.

The pin 23 is inserted through an aperture 28 in the block 10, which aperture aligns with the apertures in the bolt 21 and the collar 26 when the latter is correctly positioned on the bolt. The pin 23 is a press-fit in the bolt 21 or the collar 26 so that it remains in position but it is too short to extend into the apertures 28 in the block 10 when it has been pressed home.

In operation, with the lever 11 in the initial position shown in Fig. 1, a strip 13 is laid in the seat provided therefor in the top of the block 10 and then a yoke 15 is slipped into place with the bar 14 thereof above the slot 18. This operation can be performed with one hand and as soon as the strip and yoke are placed, the operator can swing the handle 11 clockwise with the other hand, immediately following this movement with a swing counter-clockwise, after which the handle is restored to the neutral position shown in Fig. 1 which leaves the strap folded around the bar of the yoke as shown in Fig. 4. The operator can then, without releasing the handle 11, remove the completed assembly and repeat the operation.

Various departures from the exact construction shown can be made without departing from the invention which is to be limited only to the extent set forth in the appended claims.

I claim:

1. A tool of the type described for folding a strip element around a bar element, comprising: a base member having a seat for supporting said strip element and a transverse slot intermediate the ends of said seat, whereby a strip supported

on said seat is adapted to in turn support said bar transversely thereacross above said slot, said base member being narrower at said slot than the length of said bar; and a lever member pivoted to said base member for swinging motion, said lever having a bifurcate portion adapted to straddle said seat in response to movement of said lever in one direction, the two sections of the bifurcate portions having bar-contacting surfaces thereon for engaging opposite ends of said bar projecting beyond said seat, whereby swinging movement of said lever in said one direction forces said bar down into said slot with the band extending around said bar and back up through said slot.

2. A tool as described in claim 1 in which said base member has upstanding side and end walls adjacent one end of said seat and on one side of said slot for centering said strip on said seat.

3. A tool of the type described for folding a strip element around a bar element, comprising: a base member having a seat for supporting said strip element and having a transverse slot intermediate the ends of said seat, whereby a strip on said seat is adapted to support said bar transversely thereacross above said slot; a lever member pivoted to said base member for swinging motion; means on said lever for engaging said bar member and forcing it down into said slot with the band extending around said bar and back up through said slot in response to swinging movement of said lever in one direction; means responsive to swinging movement of said lever in the other direction for squeezing the two sections of said strip together above said bar, said last means including a bolt slideable in said base member and having a head normally flush with and forming a portion of one wall of said slot; and means on said lever engageable with the rear end of said bolt in response to swinging movement of said lever in the other direction.

4. A tool as described in claim 3 in which said bolt has enlarged spaced apart portions slideable in but substantially filling a passage in said base provided therefor, and a reduced portion connecting said enlarged portions, a coil spring surrounding said reduced portion and bearing against the rear enlarged portion, and stop means projecting through said base member and said passage and engaging the front end of said spring, said stop means being in the path of movement of the front enlarged section of said bolt, whereby it limits rearward movement thereof.

WALTER E. JUDE.
